UNITED STATES PATENT OFFICE.

MAURICE ALBAUGH, OF QUINCY, OHIO.

DISPLAY CASE.

Application filed May 25, 1927. Serial No. 194,012.

This invention is a novel improvement in display cases or the like, and the principal object is to provide a display case open at the front and having a transparent top, and 5 having a plurality of spring pressed followers therein adapted to press the articles to be displayed upwardly against the transparent top, means being provided for individually depressing the followers when filling the 10 case; and means being also provided for discharging the contents of the case one at a time.

The display case is particularly adapted to be placed on the counter of a store or the 15 like, and to hold printed booklets or leaflets, such as time-tables for railway and steamship lines, catalogues, advertisements, and similar articles, which may be discharged one at a time from the display case 20 as desired.

Another object of the invention is to provide a novel display case which will display, file, and make instantly available one 25 copy at a time, any width or length of booklet, printed card, catalogue, or similar article; the features being capable of embodiment either in a portable or a "built-in" display case.

I will explain the invention with reference 30 to the accompanying drawing which illustrates one practical embodiment thereof to enable others to adopt and use the same; and I will summarize in the claims the novel features of construction, and novel construction of parts, for which protection is desired.

In said drawings:

Fig. 1 is a top plan view of the complete case, showing articles retained upon some 40 of the followers.

Fig. 2 is a front end view thereof.

Fig. 3 is a section on the line 3—3 Fig. 2.

Fig. 4 is a section on the line 4—4, Fig. 2.

Fig. 5 is an enlarged perspective view of one of the followers detached.

Fig. 6 is a bottom plan view of one end 45 of the follower showing the connection between the spring and follower.

As shown in the drawing, the display case preferably comprises a base 1, preferably 50 of rectangular shape; end members 2; and a back member 3, the upper edge of end members 2 preferably sloping slightly upwardly towards the back member 3. In the inner faces of members 2 and 3 are longitudinal grooves 2^a and 3^a disposed in the 55 same plane and adapted to receive the ends

and rear edge of a glass or other transparent plate 4, which forms the top of the case.

The front of the case is open and a strip 5, preferably of same material as the members 2 and 3, extends between the end members 2 at the upper front ends thereof, the ends of strip 5 being seated in the front ends of grooves 2^a which grooves are preferably slightly cut away as at 2^b to allow for the 60 extra thickness of strip 5 over that of the glass plate 4. Preferably the rear edge of strip 5 is grooved as at 5^a on its under side to the thickness of the glass plate 4, leaving a narrow strip 5^b which slightly overlaps 65 glass plate 4 to give a neat appearance to the top of the case.

Extending through the strip 5 in front of groove 5^a are a series of spaced aligned rectangular openings 5^c adapted to each receive 70 a roller 6, covered with a friction substance and rotatably mounted on a rod 6^a which extends the full length of strip 5 and is contained in a longitudinal groove 5^d on the axis of openings 5^c, said rod 6^a being retained 75 in the groove 5^d by means of clips 5^e overlying the groove 5^d. Rollers 6 are of diameter equal to substantially twice the thickness of strip 5 so that the roller extends 80 both above and below the said strip. 85

Within the case, at the rear thereof below the glass plate 4, is a rod 7, journaled in the end members 2, and also supported at the center in bearing 7^a mounted on the rear member 3. 90

Within the case, below each roller 6 is a follower plate 8 having its rear end pivotally connected to the hinge rod 7 such as by rolling the end of the plate around the rod 7 as at 8^a. The front end of each 95 follower plate 8 is urged upwardly against the roller 6 by means of a coil spring 9 interposed between the base 1 and the underside of follower plate 8. The upper ends of spring 9 is preferably connected to the plate 8 by means of tongues 8^b struck out from the plate 8 around the upper coil of said spring, the tongues 8^b underlying the upper 100 coil of said springs. The lower end of spring 9 may be maintained in proper position on base plate 1 by means of a lug 1^a fitting within the coils of spring 9, or any other desired manner. Any other type or arrangement of springs however may be used for urging the follower plates upwardly. 110

The forward end of each plate 8 extends

slightly beyond the front edge of strip 5 and is bent back upon itself as at 8°, the outer portion of part 8^c being bent downwardly as at 8^d through an arc of 180 degrees and 5 terminating at a point below the front edge of the body portion of plate 8, the portions 8^c and 8^d serving as a groove to receive the thumb for depressing the follower plate to insert the articles therein. To further facilitate 10 the entry of the thumb or finger into the portion 8^c the front edge of plate 8 is recessed as at 8^e.

Suitable back stops are provided on each 15 follower plate 8 to limit the entry of the articles into the case, each stop comprising a substantially L-shaped metallic strip 8^h having its vertical leg extending through a slot 8^k in the plate 8 adjacent its rear end, the horizontal leg having an elongated slot 8^m 20 for the reception of a screw 8ⁿ engaging plate 8 from the under side. Each stop 8^h is therefore adjustable longitudinally of the follower and the vertical leg extends upwardly substantially to meet the glass 25 plate 4.

Partitions 10 may also be provided for subdividing the case into a plurality of compartments containing one or more followers 8; said partitions extending the full height 30 and width of the compartment, and being notched as at 10^a at their rear edges to fit over the rod 7 and to provide bearing supports for said rod 7. The inclination of the glass plate 4 will maintain partitions 10 in 35 the display case.

In operation, the followers 8 are depressed, as above explained, and the piles of 40 articles A placed upon the followers with the front ends of the piles deposited at the front edge of strip 5. By the action of springs 9 the articles are urged upwardly so that the upper article of each pile contacts with the lower portions of the friction rollers 6. When it is desired to remove an article 45 from the case it is only necessary to rub the hand over the roller 6 in a direction towards the rear of the case, and the upper article on the respective pile will be projected forwardly out of the open end of the 50 case into position to be grasped by the hand and hence removed from the case. The article may be replaced on the pile A by depressing the follower 8 and placing the article upon the top of the pile A.

The above features may be embodied in 55 either a portable or in a "built-in" display case, and I do not limit my invention to the exact form shown in the drawings, for obviously changes may be made therein within the scope of the claims.

I claim:

1. In combination, a casing open at the front and top; a transparent closure for the top; a strip at the front edge of the closure, 60 said strip having a series of aligned open-

ings therethrough; rollers in said openings extending above and below the strip; and spring pressed followers within the casing disposed below the rollers and adapted to normally contact therewith. 70

2. In a combination as set forth in claim 1, a rod extending through the casing adjacent the rear thereof; and said followers comprising a series of plates pivotally mounted on said rod and extending beyond 75 the front edge of the strip with springs interposed between the plates and the bottom of the casing.

3. In combination, a casing open at the front and top; a transparent closure for the top; a strip at the front edge of the closure, 80 said strip having a series of aligned openings therethrough; a longitudinal groove in the lower side of said strip on the axis of said openings; a rod retained in said groove; 85 rollers mounted on said rod within said openings extending above and below the strip; and spring pressed followers within the casing disposed below the rollers and adapted to normally contact therewith. 90

4. In a combination as set forth in claim 3, a rod extending through the casing adjacent the rear thereof; and said followers comprising a series of plates pivotally mounted on said rod and extending beyond 95 the front edge of the strip; with springs interposed between the plates and the bottom of the casing.

5. In combination, a casing open at the front and top; a transparent closure for the top; a strip at the front edge of the closure, 100 said strip having a series of aligned openings therethrough; frictional rollers in said openings extending above and below the strip; a rod extending through the casing adjacent the rear thereof; follower plates 105 pivotally mounted on said rod below each roller and extending beyond the front edge of the strip and adapted to normally contact with their respective rollers; and coil springs interposed between the plates and the bottom of the casing. 110

6. In combination as set forth in claim 5; a longitudinal groove in the lower side of said strip on the axis of said openings; 115 and a rod retained in said groove; said rollers being mounted on said rod.

7. In combination as set forth in claim 5, a semicylindrical lip depending from the front end of each follower plate, the upper 120 edge thereof being recessed, for the purpose specified.

8. In a combination as set forth in claim 5, said follower plates having tongues struck therefrom adapted to engage the upper coils 125 of the springs to secure the springs thereto.

9. In a combination as set forth in claim 5; partition plates between the follower plates, said partitions having notches in their rear ends for supporting the rod. 130

10. In a combination as set forth in claim 5, said follower plates each having a slot therein; an L-shaped back stop having one leg extending upwardly through said slot; and means for adjustably connecting the other leg to the underside of the follower plate.
11. In combination, a casing open at the front and top; a transparent closure for the top; a narrow strip at the front edge of the closure, said strip having a series of aligned rectangular openings therethrough; a longitudinal groove in the lower side of said strip on the axis of said openings; a rod retained in said groove; frictioned rollers mounted on said rod within said openings extending above and below the strip; a rod extending through the casing adjacent the rear thereof; follower plates pivotally mounted on said rod below each roller and extending beyond the front edge of the strip; and coil springs interposed between the plates and the bottom of the casing to cause the plates to normally contact with the rollers.
12. In combination as set forth in claim 11, a semicylindrical lip depending from the front end of each follower plate, the upper edge thereof being recessed, for the purpose specified. 30
13. In a combination as set forth in claim 11, said follower plates having tongues struck therefrom adapted to engage the upper coils of the springs to secure the springs thereto. 35
14. In a combination as set forth in claim 11, said follower plates each having a slot therein; an L-shaped back stop having one leg extending upwardly through said slot; and means for adjustably connecting the other leg to the underside of the follower plate. 40
15. In a combination as set forth in claim 11, partition plates between the follower plates, said partitions having notches in their rear ends for supporting the rod. 45

In testimony that I claim the foregoing as my own, I affix my signature.

MAURICE ALBAUGH.
